SELF-CLEANING DRILL STRING TOOL

James H. McManus, Jr., Box 1994, Lafayette, La. 70501

Filed Dec. 10, 1964, Ser. No. 419,275

19 Claims. (Cl. 175—313)

This is a continuation-in-part of pending application Ser. No. 381,780 filed July 10, 1964. The present invention relates generally to well drilling equipment, and more specifically to certain new and useful improvements in the construction of drill string tools which are self-cleaning.

Drill string tools such as stabilizers and reamers perform many functions including preventing the drill from spiralling during drilling, and insuring that the drill hole does not collapse or contract in diameter and thus prevent removal of the drill.

The main disadvantage of presently known devices of this class is the tendency for the blades of the tool to become clogged, or in the parlance of the field, "balled-up." Such a condition is caused by agglomeration of materials such as wall cake and cuttings into a hard ball surrounding the blades of the tool. When "ball-up" is encountered, premature removal of the drill string from the drill hole is required in order to free or clean the blades. Otherwise, drilling mud circulation ultimately is blocked by the ball and upwardly applied force is exerted on the drill string. This upwardly applied force effects a diminution of the predetermined running weight on the drill bit and, accordingly, a corresponding decrease in drilling rate. Additionally, this upward urging of the drill string causes the bit to walk off the bottom of the hole and often results in a crooked drill hole and, consequently, stuck pipe. Any decrease in the drilling rate and/or shut downs due to stuck pipe obviously adds materially to the cost of the well.

Further, as the pressure from the drilling fluid builds up below a "balled-up" tool, the wall formation of the bore hole often is broken down and circulation is lost. In many instances, the drilling tools currently available have been directly responsible for the added operating expense of restoring circulation, the cost of lost-circulation material and the cost of replacing the mud system.

Accordingly, it is a primary object of this invention to provide a drill string tool which is self-cleaning.

Another object of this invention is to provide a drill string tool which is capable of removing balled-up material from its surface while it is in the drill hole.

Still another object of this invention is to provide a drill string tool having blades adapted to move axially relative to the drill string and the bore of the drill hole in order to overcome problems presently experienced with tools of this class.

An additional object of this invention is to provide a drill string tool which can clean the area between the blades while the drill string is in the drill hole.

A further object of this invention is to provide a drill string tool which can clean the blades of the tool while the drill string is in the drill hole.

A specific object of this invention is to provide a combination stabilizer and reamer tool which is self-cleaning, is ruggedly constructed to perform efficiently and accurately during drilling operations, and which eliminates the "balling-up" heretofore encountered with such tools and the problems resulting therefrom.

Additional objects and advantages of this invention will become apparent from the following description and drawings.

In accordance with the present invention, it has been found that drill string tools may be made self-cleaning and thus overcome many of the disadvantages of prior art tools. The self-cleaning is provided by permitting relative longitudinal movement between the stabilizing and/or

2

reaming blades and the tool housing and by incorporating a wiping means on the tool to remove balled-up material during such relative movement.

Generally described, the present invention is a self-cleaning drill string tool having in combination a sleeve having means at one end to connect said sleeve to the drill string, said sleeve having at least one elongated slot; a mandrel slidably mounted in said sleeve with one end of said mandrel directed out of said sleeve, said one end of said mandrel having means to connect said mandrel to the drill string; at least one blade mounted on said mandrel and extending through a portion of an elongated slot in said sleeve and being slidable in the slot; and wiper means mounted on said blade adjacent said sleeve whereby the sliding of said blade in the slot of said sleeve will cause said wiper means to wipe caked material therefrom.

In accordance with a preferred embodiment of the invention, the sleeve has a plurality of slots spaced about its periphery, the mandrel has a corresponding plurality of blades extending through the slots and the wiper means is an annular band mounted in a slot in each of the blades. It is preferred that the blades be elongated and that one wiper band be mounted at each end of the blades.

In a further embodiment of the invention, the tool is equipped with wiper means such as studs mounted on the sleeve on each side of the slot or slots to wipe caked material from the blades as the blades reciprocate in the slots. The wiper studs may be used in conjunction with the wiper bands or they may be used alone. Preferably both studs and bands are employed.

It is desirable that the slots in the housing be about twice as long as the blades to allow the wiper means to move substantially along the entire surface of the portion of the sleeve between the blades and to allow the wiper studs to move along substantially the entire sides of the blades. If desired, the slots and blades may be helical.

This invention having been generally described, the preferred specific embodiments will be described in detail with reference to the accompanying drawings.

FIGURE 1 is a plan view of a tool constructed in accordance with the teachings of this invention with the sides partly broken away and in cross section so as to reveal the several elements contained therein.

FIGURE 2 is a cross section taken along line 2—2 of FIGURE 1.

FIGURE 3 is a cross section taken along line 3—3 of FIGURE 1.

FIGURE 4 is a cross section taken along line 4—4 of FIGURE 1.

FIGURE 5 is a perspective view partially in section of another tool constructed in accordance with the teachings of this invention illustrating the tool in the retracted position.

FIGURE 6 is a perspective view partially in section of the tool of FIGURE 5 illustrating the tool in the extended position.

Referring now to the drawings in detail, the numeral 5 represents an elongated cylindrical housing consisting of an upper portion 6 having a cylindrical surface 7 of constant diameter. The lower portion 8 is a continuation of the upper portion but has a slightly reduced diameter forming an outer cylindrical surface indicated at 9. The upper end 10 of the housing is formed with a female tapered thread connector 11 which communicates with a concentric central passage 12 through which drilling mud is pumped as in conventional drilling practice. The central passage communicates with an enlarged bore 13 which extends concentrically through both the upper and lower portions 6 and 8 of the housing. The lower portion of the housing is provided with three radial slots 14 which are symmetrically positioned and extend longitudinally thereof to terminate at 15 short of the cylind-

drical surface 7. Three guide grooves 16 are machined in the lower portion 8 intermediate the radial slots 14 and extend beyond the slots to terminate at 17 within the bore 13 of the upper portion 6. Similar grooves 18 extend along the enlarged bore in the plane of the radial slots 14 beyond their terminating points 15. The lower end 19 of the housing 5 is provided with a tapered male connecting thread 20 which receives a split nut 21, the nut being ultimately welded in position after assembly. A small split bearing ring 22 is received in the lower end of the enlarged bore 13 and is maintained therein by the flanges 23 of the split nut 21.

The second major component of this tool comprises a mandrel 24. The mandrel has a lower portion 25 of cylindrical section equal to that of the housing 5. The end of this portion terminates with a male tapered thread 26 of standard pitch, and a central concentric passage 27 extends through the mandrel to provide passage for drilling mud. Continuing upwardly from the lower portion 25 the mandrel is provided with a reduced cylindrical section 28 which upon assembly slidably engages within the split bearing ring 22. The section 28 is interrupted by three radially extending cutter blades 29 having tapering end walls 30 and a cutting edge 31 which describes a circumference greater than that of the housing. Extending upwardly from the cutter blades 29 are splines 32 which are slidably received in the guide grooves 16 and 18 of the housing. The mandrel continues with a further cylindrical section 33 which is machined for a clearance association with the enlarged bore 13 and terminates with a threaded portion 34, and finally with a smaller cylindrical end piece 35 to complete the mandrel.

It will be clear that the cutter blades 29 extend through the radial slots 14 and are free to move along the length of the slots. Movement is restricted by a packer and spring assembly which is located at the inner end of the enlarged bore 13. This assembly starting at the innermost end of the bore consists of a sleeve 36 formed with a central passage 37 for alignment with the passage 12. The inner end of the sleeve is tapered as indicated at 38. Seated in the tapered portion of the sleeve is a spring holder 39 having a plug portion 40 of lesser diameter than the bore 13 to receive and guide one end of a compression spring 41. The spring holder has a central passage 42 to form a continuation of the passage 37. The packing is mounted over the end piece 35 and consists first of a brass ring 43 which is internally threaded for engagement on the threaded portion 34 of the mandrel. Next adjacent the ring 43 is a lead ring 44 which abuts with a rubber packer sleeve 45. An end sleeve 46 has a tapered rim 47 which abuts with one end of the second spring holder 48. The spring holder 48 has a plug portion 49 for mounting the other end of the spring 41. It is also provided with a counterbore 50 for sliding engagement over the cylindrical end piece 35 and permitting clearance beyond the end of the end piece such that the several packing elements become constantly under compression by the compression spring. The spring holder also has a central passage 51 to form a continuation of the passage 27 which extends through the mandrel. It will also be appreciated from the drawings that all of the elements in the packer and spring assembly just described have an external diameter equal to that of the enlarged bore 13 in the housing.

Two steel wiper bands 52 are adapted to slidably engage over the cylindrical surface 9 of the lower portion 8 of the housing so that they may slide along the surface of the housing and wipe caked material therefrom. Bands 52 are received in small slots 53 formed in the end walls 30 of the cutter blades 29. The bands are assembled one at each end of the cutter blades.

The embodiment of the invention shown in FIGURES 5 and 6 illustrates in an enlarged scale various modifications of the tool.

Referring to FIGURES 5 and 6, it may be seen that the

tool has a housing or sleeve 60 with a longitudinal passageway 62 extending therethrough. Passageway 62 has an enlarged portion 64 at one end to receive a mandrel 66. Four helical slots 68 are located about the periphery of housing 60. The lower end of housing 60 is threaded at 70 to receive a nut 72 which holds a bearing ring 78 in place.

Mandrel 66 is slidably mounted in enlarged passage-way 64 and has four helical blades 76 mounted thereon. 10 Each of the blades extends through one of slots 68. The blades are free to slide in the slots but are restricted in their movement at one end by the end of the slots and at the other end by the bearing ring 78 mounted in nut 72. Wiper studs 74 are mounted on housing 60 adjacent each 15 of slots 68 with one wiper stud on each side of each slot. Each of blades 76 is in sliding engagement with the pair of wiper studs 74 mounted adjacent the slot through which the blade extends.

Mandrel 66 has helical splines which slide in helical 20 grooves in the housing 60 to transmit rotary motion between the housing and the mandrel. Except for being helical these splines and grooves are substantially the same as those illustrated in FIGURES 2 through 4.

A pair of annular wiper bands 80 and 82 are mounted 25 in slots 84 in the ends of blades 76 with one band being mounted on each end of the blades. Alternatively, the wiper bands may be made in curved segments with the segments extending between adjacent blades. The wiper bands have a sliding clearance with housing 60 so that as 30 the blades 76 slide in slots 68, wiper bands 80 and 82 will slide along the surface of housing 60.

A packing 88 is mounted on an extension 86 of mandrel 66. The packing which may be of any conventional type is illustrated here as having two groups of packing elements urged apart by a spring 92. One group abuts mandrel 66 at the junctions of extension 86 and the other group abuts a snap ring 90 mounted in a seat 91 at the end of extension 86. Mandrel 66 has a longitudinal bore 94 which communicates with bore 62 of housing 60 for 40 allowing drilling fluids to be passed through the tool. Packing 88 permits mandrel 66 to slide in housing 60 while at the same time permitting drilling fluid to pass through passageways 62 and 94.

The end 95 of mandrel 66 is threaded to receive a 45 tool joint 96 for connecting one end of the tool to the drill string. Similarly, the tool is connected at its other end to the drill string by threads (not shown) on the end of housing 60.

In use, the tool may be mounted in the drill string 50 with either end extending upwardly. Specifically, the mandrel may be connected to the portion of the drill string leading to the bit and the housing to the portion of the drill string leading out of the drill hole or the housing may be connected to the portion of the drill 55 string leading to the bit and the mandrel may be connected to the portion of the drill string extending out of the drill hole. The tool will operate equally well in either position.

Referring specifically to the embodiment illustrated 60 in FIGURES 1 through 4, it will be seen that after the tool has been mounted on the drill string and is lowered into the drill hole, the weight applied to the drill string will cause the tool to retract mandrel 24 within housing 5. During the drilling operation, drilling fluids are 65 pumped through the drill string and pass through passageways 12 and 13 of housing 5 and passageway 27 of mandrel 24.

To clean the tool when materials such as cuttings, 70 wall cake and drilling fluids collect in a ball about the blades of the tool, the operator simply picks up on the drill string. Assuming that the mandrel is connected to the portion of the drill string leading to the bit and the housing is connected to the portion of the drill string leading to the surface, this picking up causes housing 75 to slide upwardly of mandrel 24 to the position illus-

trated in FIGURE 1. As the housing slides upwardly, grooves 16 slide upwardly along splines 32 and thus rotating of the drill string at the surface of the drill hole will continue to rotate the mandrel and hence the drill bit.

The sliding of the housing causes slots 14 to slide upwardly along blades 29. The movement of the portion of the surface of the housing extending between slots 14 past wiper bands 52 causes balled-up material on this portion of the housing to be sheared from the housing by wiper bands 52. While two wiper bands 52 are illustrated, it will be apparent that if desired the upper wiper band could be eliminated since the lower wiper band cleans the portion of the surface of the housing which is normally between the blades and very little balling up will occur in the short period of time during cleaning in which the blades are in the lower ends of the slots.

The material which has been sheared from the tool is carried to the surface of the drill hole by the drilling mud which is passing upwardly between the walls of the drill hole and the drill string. Once the operator has picked up on the drill string, he immediately lets it down allowing the normal running weight to once again slide housing 5 down over mandrel 24. During this sliding movement, wiper bands 52 once again shear off any material adhering to the portion of the surface of housing 5 between slots 14.

If the tool is inverted in the drill string with mandrel 24 connected to the portion of the drill string leading to the surface of the drill hole and housing 5 connected to the portion of the drill string leading to the bit, the picking up and letting down of the drill string will slide the mandrel up and down in the housing rather than sliding the housing up and down on the mandrel. The wiping action will be similar to that described above only wiper bands 52 will move along the surface of the housing, rather than the housing moving beneath the wiper bands.

Thus, it may be seen that the balled-up material may be cleaned from the tool without removing the tool from the drill hole. By picking up on the tool every thirty minutes to two hours, the operator can keep the tool from being balled up and eliminate the attendant disadvantages normally found in tools not having a self-cleaning feature.

The operation of the embodiment illustrated in FIGURES 5 and 6 is similar to the operation of the embodiment described above. Here, however, the blades and slots are helical. Thus if housing 60 is connected to the portion of the drill string leading to the surface of the drill hole and mandrel 66 is connected to the portion of the drill string leading to the bit, the picking up of the drill string will cause housing 60 to move from the position illustrated in FIGURE 5 to the position illustrated in FIGURE 6.

The upward movement of the housing causes the helical grooves in housing 60 to slide over the helical splines in mandrel 66, thus slightly rotating mandrel 66 with respect to housing 60 and allowing helical slots 68 to slide upwardly past helical blades 76. The upward movement of housing 60 causes wiper bands 80 and 82 to shear balled-up material from the portion of the surface of housing 60 which is between slots 68. Wiper studs 74 provide an additional wiping action by shearing any caked material from the sides of blades 76 as the wiper studs pass along blades 76. Similarly, the downward movement of housing 60 accompanying the letting down of the tool causes wiper bands 80 and 82 to once again move across the housing and blades 76 to once again move past wiper studs 74 shearing any newly collected material from the housing and blades, respectively.

If the tool is inverted in the drill string with mandrel 66 connected to the portion of the drill string leading

to the surface and housing 60 connected to the portion of the drill string leading to the bit, the mandrel will be slid up and down in the housing rather than the housing being slid up and down on the mandrel.

Thus, the upward movement of the mandrel will cause the helical splines and grooves to rotate the housing 60 with respect to the mandrel to allow helical blades 76 to slide upwardly in helical slots 68. The wiping action will be similar to that described above, only the wiper bands 80 and 82 will move along the surface of the housing, rather than the housing moving beneath the wiper bands and the helical blades will move along wiper studs 74, rather than the studs moving along the blades.

Though either of the embodiments may be used as reamers, stabilizers or combination reamers and stabilizers, the helical blades are particularly useful when the tool is used as a stabilizer since the blades will contact a greater area of the wall of the drill hole as the tool moves through the hole. This greater area of contact makes the stabilizer more effective since it is less likely to be affected by longitudinal irregularities in the wall of the drill hole.

In summary, the advantages are several. The tool will produce a true gauge hole which is straight and due to longitudinal movement of the blades, balling up of the blades is averted and good circulation of drilling fluid is assured. The elimination of the balling-up effect permits the desired weight to be put on the drilling bit since there will be no drag caused by the blades. As a result of these advantages, the drilling rate is increased and the entire drilling string works with more reliability and precision.

There has been illustrated and described what are considered to be preferred specific embodiments of the invention. It will be understood however that modifications and variations of this invention will become readily apparent to those skilled in the art without departing from the scope of the invention which is defined in the appended claims.

I claim:

1. A self-cleaning drill string tool comprising in combination: a sleeve having means at one end to connect said sleeve to the drill string, said sleeve having at least one elongated slot; a mandrel slidably mounted in said sleeve with one end of said mandrel directed out of said sleeve, said one end of said mandrel having means to connect said mandrel to the drill string; at least one blade mounted on said mandrel and extending through a portion of an elongated slot in said sleeve and being slidable in the slot; and wiping means mounted on said blade adjacent said sleeve whereby the relative sliding of said blade and the slot of said sleeve will cause said wiping means to wipe caked material therefrom.

2. The tool of claim 1 wherein said slot and said blade are helical.

3. The tool of claim 1 including at least one wiper stud mounted on said sleeve adjacent said slot whereby relative sliding of said blade and the slot will cause said stud to wipe caked material from said blade.

4. The tool of claim 1 wherein said sleeve has a plurality of slots spaced about its periphery, and said mandrel has a plurality of blades extending through said slots.

5. The tool of claim 4 wherein said slots and said blades are helical.

6. The tool of claim 4 including wiper studs mounted on said sleeve on each side of the slots whereby the relative sliding of said blades and the slots will cause said studs to wipe caked material from said blades.

7. The tool of claim 4 wherein said wiping means comprises an annular band mounted on said blades and extending around said sleeve.

8. The tool of claim 7 including wiper studs mounted on said sleeve on each side of said slot whereby the relative sliding of said blades and the slots cause said studs to wipe caked material from said blades.

9. The tool of claim 7 wherein said blades are elongated and two annular wiper bands are mounted on said blades with one wiper band being at each end of said blades.

10. The tool of claim 9 including wiper studs mounted on said sleeve on each side of the slots whereby the relative sliding of said blades and the slots will cause said studs to wipe caked material from said blades.

11. The tool of claim 10 wherein the slots are about twice as long as said blades.

12. The tool of claim 10 wherein said blades and the slots are helical.

13. The tool of claim 12 wherein the slots are about twice as long as said blades.

14. A self-cleaning drill string tool comprising: a sleeve having means at one end to connect said sleeve to the drill string, said sleeve having at least one elongated slot; a mandrel slidably mounted in said sleeve with one end of said mandrel directed out of said sleeve, said one end of said mandrel having means to connect said mandrel to the drill string; at least one blade mounted on said mandrel and extending through a portion of the elongated slot in said sleeve and being slidable in the slot; and wiping means mounted on said sleeve adjacent said slot whereby the relative sliding of said blade and the slot will cause said wiping means to wipe caked material from said blade.

15. The tool of claim 14 wherein the slot and said blade are helical.

16. The tool of claim 14 wherein said sleeve has a plurality of slots spaced about its periphery, and said mandrel has a plurality of blades extending through said slots.

17. The tool of claim 16 wherein the slots and said blades are helical.

18. The tool of claim 16 wherein said wiping means are studs and one stud is mounted on said sleeve on each side of slots whereby the relative sliding of said blades and the slots cause the studs to wipe caked material from said blades.

19. The tool of claim 18 wherein the slots and the blades are helical.
